UNITED STATES PATENT OFFICE.

SAMUEL T. WINDSOR, OF NORMANGÉE, TEXAS.

AUXILIARY TRANSMISSION-CASE HANGER.

1,215,603.

Specification of Letters Patent. Patented Feb. 13, 1917.

Application filed April 25, 1916. Serial No. 93,510.

To all whom it may concern:

Be it known that I, SAMUEL T. WINDSOR,
a citizen of the United States, residing at
Normangee, in the county of Leon and State
5 of Texas, have invented a new and useful
Auxiliary Transmission-Case Hanger, of
which the following is a specification.

The present invention appertains generally to automobiles, and relates more particularly to a device for supporting the transmission case from the frame or chassis.

It is the object of the invention to provide a novel and improved auxiliary hanger applicable to the frame and transmission case of a Ford automobile, although the device can be constructed for application to other automobiles, whereby the hanger when applied will effectively support and reinforce the transmission case. The present device may be used in emergency cases when one or both of the usual transmission case hangers break, or the device can be used as an auxiliary hanger for supporting the transmission case, to avoid the possible displacement thereof when the car is subjected to hard usage.

It is also within the scope of the invention to provide an appliance of the nature indicated which is extremely simple and inexpensive in construction, which can be readily applied, and which will serve its office in a thoroughly efficient and satisfactory manner.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein:—

Figure 1 is a side elevation of the transmission case and a fragmental portion of the frame showing the auxiliary hanger applied thereto.

50 Fig. 2 is a vertical section taken on the line 2-2 of Fig. 1.

In the drawing, there is designated at 1 the side beams of the automobile frame or chassis, between which the transmission case 2 is mounted, said case being hung from the beams 1 by the usual hangers 3, which some-
55

times break or become injured due to the jars or strains to which the machine is subjected. The transmission case 2 is provided at its lowermost point with a depending pocket or portion 4 for the collection of sediment, which is utilized as a means for applying the present hanger to the transmission case. 60

The present attachment embodies a pair of inclined or upwardly diverging rods 5 provided at their upper ends with forks 6 overlapping the outer sides of the beams 1 and straddling the hangers 3, the upper ends of the branches or arms of the fork being formed into hooks 6 seating upon and engaging behind the beams 1 at the opposite sides of the hangers 3. Thus, the rods 5 can be readily applied to the beams 1, and will be effectively held in place by the hangers 3.

The device includes a third rod 8 bent at an obtuse angle to fit the lower portion of the transmission case 2, as seen in Fig. 2, and said rod 8 is provided intermediate 30 its ends with a loop 9 surrounding the portion 4, whereby to effectively assemble the rod 8 and case 2, to prevent their relative displacement. The rod 8 is provided at its ends with outturned eyes 10 slidably embracing the rods 5, and nuts 11 or other retaining elements are engaged upon the lower terminals of the rods 5 and bear upwardly against the eyes 10, whereby the rod 8 is supported from the rods 5. The nuts 11 can be tightened, whereby the auxiliary hanger will be tightened to support the transmission case 2 from the beams 1. 35 40

The present attachment can be readily applied to and removed from the transmission case and frame, and when applied occupies but little space, although it serves its function in a practical and desirable manner. 95

Having thus described the invention, what is claimed as new is:

1. An auxiliary transmission case hanger embodying a plurality of rods certain of which have remote terminals extending upwardly to rest against the outer sides of the beams of an automobile chassis, said terminals having inturned hooks for engaging and seating upon said beams, the rods being adapted to extend under and support a transmission case between said beams, and means adjustably connecting the rods. 110

means adjustable connecting the rods.

2. An auxiliary transmission case hanger embodying a pair of rods having hooks to

engage the side beams of an automobile frame, an intermediate rod having means between its ends for engaging the lower portion of a transmission case, the ends of the intermediate rods being slidably connected to the pair of rods, and means upon certain rods for adjusting them relatively to one another.

3. An auxiliary transmission case hanger embodying a pair of rods having forks whose arms are formed into hooks to engage over the side beams of an automobile, an intermediate rod having a loop between its ends to engage the lower portion of a transmission case, and means adjustably connecting the ends of the intermediate rod with the aforesaid rods.

4. An auxiliary transmission case hanger embodying a pair of rods having upper forks whose arms are formed into hooks to engage over the side beams of an automobile, an intermediate rod having a loop between its ends to engage the lower portion of a transmission case and having eyes at its ends slideable upon the aforesaid rods, and retaining elements upon the first mentioned rods to bear against said eyes.

In testimony that I claim the foregoing as my own, I have hereto affixed my signature in the presence of two witnesses.

SAMUEL T. WINDSOR.
